PULLING TOOL FOR VALVE GUIDE KEEPERS

Arthur T. Hansord, Minneapolis, Minn.

Application March 1, 1946, Serial No. 651,165

1 Claim. (Cl. 29—249)

1

This invention relates to a tool for removing valve guide keepers from the motor blocks of automotive engines.

In automotive engines, particularly those of the V-block type, the stems of the tappet valves are guided by a split, tubular mechanism which is retained against longitudinal displacement in the respective valve discharge or intake passage by means of a bifurcated, flat retainer plate having an integral tab or tongue to facilitate insertion and removal thereof. The said retainer plates are applied internally of the block with a cap of the block removed and after considerable use, become very firmly locked with the grooves of the split valve guide and are removable from within the block only with considerable difficulty. To facilitate removal the guide retainers or keepers are provided with a tool-engaging aperture near the extremity of the tabs to accommodate the pin of the prying tool, which is adapted to dislodge and pull the plates inwardly into the interior of the block. The force required for dislodging and pulling these keeper plates is so great that in many instances, the stock of the tab is sheared by the pin when pulling pressure is applied, the metal weakening before sufficient force is exerted on the body of the plate to dislodge the same from the valve guide and inner wall of the block.

It is an object of my invention to provide an extremely simple but highly efficient pulling tool by which said valve guide retainers or keeper plates may be easily and speedily removed without danger of shearing the apertured tabs by which connection is made.

More specifically, it is an object to provide a pulling tool of the class described wherein the initial operation of the tool connected with the apertured tab, is to bend the tab transversely about the extremity of the tool, thereby forming a snubbing portion and to thereafter apply leverage to push the keeper or retainer plate outwardly, distributing the strain between the snubbing surface and the apertured portion of the tab.

Another object is the provision of simple and highly efficient method for removing valve guide keepers from the blocks of automotive engines which consists essentially in first engaging the apertured portion of the tab of a keeper plate, then applying a bending force upon the tab to fold the same transversely over a snubbing edge and then applying a pulling force, distributed between the snubbing edge and the apertured portion of the tab to withdraw the keeper without danger of breaking the metal in the tab.

These and other objects and advantages of my invention will be more apparent from the following description made in connection with the accompanying drawings wherein like reference characters refer to the same parts throughout the several views and in which:

2

Fig. 1 is a side elevation of an embodiment of my tool;

Fig. 2 is an end elevation of the same;

Fig. 3 is a vertical fragmentary cross section of an automotive engine motor block with the head detached, showing the step of connecting the extremity of my tool with the valve guide keeper or retaining plate and showing in dotted lines, the initial operation of the tool prior to bending the snubbing portion of the tab;

Fig. 4 is a similar fragmentary section of the same block, illustrating the next two steps in the removal of the keeper with my tool;

Fig. 5 is a plan view of one of the keepers or retaining plates detached before the tab has been bent;

Fig. 6 is a side elevation of the same; and

Fig. 7 is a fragmentary view of the working end of my tool taken partially in side elevation and partially in longitudinal section and showing the snubbing relation of the bent tab of the keeper with the novel structure of the tool.

As shown in the drawings, my pulling tool comprises an elongated, rigid bar or lever 10 which may be conveniently constructed from integral metal rod material having as shown, a roughened or knurled handle portion 10a and having its working extremity provided with a short offset portion 10b formed as shown, by first bending the outer end of rod 10 at slightly less than right angles from the body or shank thereof and then again bending the extremity substantially at right angles to the said angled portion and extending substantially parallel to the shank or body 10. The offset working end 10b of the tool is flattened at its extremity along a plane 10c which extends at an acute angle preferably between 50° and 60° to the longitudinal center line of the shank or body of the tool. A rigid tab engaging pin 11 preferably constructed of hard steel, extends outwardly from the extremity 10c and may be conveniently secured by shrinking or other process in a suitable socket drilled in the extremity of the tool. The pin 10 preferably

30 is not disposed quite normal to the plane of extremity 10c but extends at an angle thereto of from 70° to 80°.

The outer longitudinal surface of the offset, working end 10b of the tool is flattened to intersect the planar extremity 10c, thereby defining a short and straight V-shaped folding edge 10d.

In Figs. 3 and 4, the several steps of removing a valve keeper plate from the block of an automotive engine, are illustrated. The portion of the block shown includes a part of one of the conventional cylinders C, having therein, the usual piston P and having the usual water jacket W surrounding the cylinder and the diagonal partition D which with the upper corner of the casting, defines one of the valve passages VP communicating with a beveled, circular valve seat

wherein the poppet valve V is seated. Poppet valve V has the usual axial stem S spaced at its lower end the requisite distance of clearance from the tappet T. In some internal combustion motors, a split valve guide G is utilized, the two longitudinally channeled members of the guide surrounding the stem S and constituting a slide bearing therefor and together, having a head portion which snugly fits a cylindrical passage in the block disposed axially below the valve seat. The two channeled sections of the valve guide G are held together or retained by a bifurcated keeper or retainer plate K which is of conventional form and shaped when inserted and in use as illustrated, in Figs. 4 and 5. This keeper plate K, it will be noted, has a flat body provided with a wide slot terminating in an arc whereby the semi-annular grooves in the medial portion of the valve guide members are engaged and locked together. The keeper is provided with an insertion and pulling tab KT which extends laterally from the body and in a plane disposed at an angle of approximately 30° to the upper surface of the body. The tab KT is provided with an aperture KA adjacent its outer end for engagement with the pin of a pulling tool. The valve structure as shown, is provided with the usual helical spring H interposed between the lower end of the valve guide and a member attached to the tappet end of the stem to urge the valve downwardly and inwardly against its operating tappet.

In Fig. 3 the working end of my improved tool is shown in full lines as the pin 11 is about to be engaged with the apertured portion KA of the inclined tab of the keeper. In this connection, it will be noted that when the pin 11 is engaged with the aperture, the longitudinal outer surface of the short, offset portion 10b of the tool bears against the diagonal partition D of the block and acts as a fulcrum for the subsequent swinging movements of the tool. The tool is first moved after engagement of the pin from the full line position to the dotted line position of Fig. 3 wherein the tab KT is bent somewhat downwardly and the working end of the tool is shifted downwardly as shown in Fig. 3. The tool is further swung as a lever fulcrumed on the curved contour of the offset portion 10b against the diagonal partition D, thereby bending the medial portion of the tab KT sharply against the straight V-shaped edge 10D at the extremity of the tool and causing the extremity of the tab KT of the keeper plate to frictionally engage and lie flush against the planar terminal surface 10c and to further, be tightly drawn about the folding edge 10d as shown in the full lines in Fig. 4. Thereafter, further swinging of the tool lever 10 on the fulcrum of the curved portion of the offset end snubs the keeper more tightly against the planar surface 10c and the sharp edge 10d and dislodges the plate by pushing action. The dotted lines in Fig. 4 indicate the moved position and bending of the keeper K just prior to its complete release from the valve guide.

In the said steps of my method and operation of the working end of the tool, the tab KT is first engaged and without exerting displacement pull upon the keeper, is bent transversely to snub the outer portion thereof against the planar surface 10c at the extremity of the working end and against the sharp, straight edge 10d, all before pulling strain is exerted upon the body of the keeper to dislodge the same. Thereafter, the strain of removing the keeper from the valve guide

is divided by pushing force between the snubbed portions of the keeper tab and the apertured extremity of the tab engaged by pin 11. The distribution of this keeper-removing force is such that at least 50% and it is believed, in excess of 60% thereof is imposed upon the snubbed portion of the keeper tab rather than upon the apertured, narrow portion engaged by the pin.

In the extensive use of my device, the keepers 10 are uniformly removed easily and quickly without rupture of the narrow extremity of the keeper tab just outwardly of the aperture.

With tools of the prior art extensively used prior to my discovery in a very large percentage of cases, the pulling strain imposed upon the keeper tab severed the narrow portion of metal disposed outwardly of the pin-receiving aperture with the result that subsequent removal of the keeper became extremely laborious and required considerable time and labor.

With my improved construction, through the distribution of the pushing force and the snubbing action obtained, the valve guide retainers or keepers may be easily and quickly removed even though very tightly adhering to the block and grooves in the valve guide.

Fig. 7 accurately shows the snubbing engagement of the bent tab of the keeper with the working end of my tool just prior to application of the actual force for removing the body of the keeper.

It will of course, be understood that various changes may be made in the form, details, arrangement and proportions of the parts without departing from the scope of my invention.

What I claim is:

A tool for pulling a keeper having an apertured tab comprising an elongated shank portion, an offset portion at the end of said shank portion at substantially right angles thereto, and a terminal portion extending from the end of said right-angledly disposed portion in a direction away from said shank and substantially parallel thereto, said terminal portion terminating in a planar end face disposed at an acute angle to the longitudinal center line of the said shank, a portion of the side of said terminal portion outermost of the shank being flat and intersecting said planar end face to provide a V-shaped configuration in cross section and presenting an outer straight folding edge, an aperture engaging pin on said planar face spaced from said folding edge and the zone of said tool connecting said offset and the terminal portions affording a fulcrum whereby the tool may pivot to bend a tab over said edge to provide a snubbing grip on a tab to augment the force applied by the pin in a keeper pulling operation to prevent rupturing of the tab.
